United States Patent Office.

HERMANN VASSEUR, OF WALLINGFORD, CONNECTICUT, ASSIGNOR TO SIMPSON, HALL, MILLER & CO., OF SAME PLACE.

Design No. 3,891, dated March 8, 1870.

DESIGN FOR AN ICE-PITCHER.

The Schedule referred to in these Letters Patent and making part of the same.

To all whom it may concern:

Be it known that I, HERMANN VASSEUR, of Wallingford, in the county of New Haven, and State of Connecticut, have invented a new Design for Ice-Pitcher; and I do hereby declare the following, when taken in connection with the accompanying illustration and the letters of reference marked thereon, to be a full, clear, and exact description of the same, and which said illustration constitutes part of this specification, and represents a side view of two pitchers of the same design, differing only in ornamentation.

This invention relates to a design for ice-pitcher. The base of the pitcher is contracted from a bead, A, down, tapering up to the neck-band B, which is of little larger diameter than the pitcher at the neck.

The cover is of molded form, and terminating in an ornament. The spout is in the form of a bracket or truss, and the handle angular, projecting directly out from the pitcher under the neck, then running down to near the base of the body. The ornamentation of the body of the pitcher, by chasing or otherwise, is no part of my invention, my invention relating to the shape and general outline only.

I claim as my invention—

The design for ice-pitcher as described and shown.
HERMANN VASSEUR.
